The sliding link 92, as shown, is turned up at right angles at the end opposite the follower and carries a pivot 98 by which it is connected to a plate 99, forked or slotted at 5 100 to engage a stationary pivot pin 101 on the frame, the plow 81 being rigidly secured to the plate 99 by any suitable means, as rivets 102. The follower 94 is held in contact with the cam surface by means of a tension spring 104 connected at one end to the plate 99 and at the other to a pin on the machine frame.

As I have pointed out, the link 92 is a rigid member sliding in a fixed rectilinear guide-way 93 so that all parts of the link 92, including the pivot 98, move in a straight line and as the lower end of the plow is immediately adjacent the pivot 98, the plate 99 being rigidly connected to the plow, said 15 end of the plow likewise has a substantially parallel motion, the slot 100 moving up and down relatively to the pin 101 to compensate for the variation of the path of the pivot 98 and the point of the plow 103 from a true 20 circular arc. Thus we have not only a change of position but a change of direction of the guide sufficient to provide for the change of direction or angle to each other at which the two parts of each flap 27 are set.

It will be noticed that the bottom folder rollers, which may be properly termed pressing rollers 85, have their full diameter sections so placed that they contact directly in line with the ends of the plows so that 25 the blank with the flaps turned over and pasted is received immediately into these rollers which engage the edges, particularly the folded flaps, pressing them tightly into place and completing the operation of the 30 pasting.

From the folder rollers, the seal passes downward between the belt 105 and the drying wheel 106, the belt being driven by a small pulley 107 on the drive shaft 108 and passing over guide pulleys 109, 110, 111 and 112, spaced about the periphery of the drying wheel which is driven in any suitable manner, as by a belt 113 from a pulley 114 on the shaft of the lower doubling roller 35 and train of gearing 115. After passing around the drying wheel between the drying wheel and the belt which serves to hold them in pasted position, the seals or envelops are partially dry, sufficiently to keep 40 them in a folded or pasted position until completely dry, and they are accordingly delivered from the machine at the point where the belt passes around the pulley 112.

While the operation of the machine has 45 been brought out in connection with the description, it will be reviewed for the purpose of clearness.

The paper web in the roll 3 is drawn over the take-off rollers 6 by the feed rollers 8 50 and 9 whence it is fed to the cutting roll-

ers shown as equal in circumference to the length of the blank provided with a blade or cutter on the upper roller of an outline similar to the blank as shown in Fig. 12, but having a gap or opening 23' in the transverse portion 120 corresponding to the ends 24 and 25 which, it will be understood, are preferably formed by this single cutting edge severing the rear end of each blank from the forward end of the next succeeding 55 blank. The blanks are intended to be led through the machine, each being drawn forward by the next preceding and therefore kept connected in the form of a single piece of material until severed by the blade 75 on 60 the folding roller 5 which is of a width equal to or slightly greater than the aforesaid gap in the transverse portion of the blade. From the cutting rollers, see Fig. 6, the blanks thus connected are led forward to 65 the scoring rollers, the upper one of which is provided with a blunt edge in the form of the dotted lines on the blank, see Fig. 12. The blunt edge is pressed against the paper which is supported on the lower roller 70 compressing the fibers along the line thus engaged, forming a score or line along which the paper is easily folded without cutting or weakening the fiber. From the scoring rollers, see Fig. 7, the blanks still connected 75 as described, are led to the paste rollers, the upper roller of which is formed with a raised portion 47, see Fig. 8, conforming to the outline of the flaps 27, 28 and 29 80 between the dotted lines 30 and the outer edges of the blank. These raised portions are coated with paste by means of the roller 44 fed from the paste pot 45. From the paste rollers, the blanks are fed forward to 85 the doubling rollers 50 and 51 which operate as already described, the center of the blank defined by line 26 in Fig. 12 being gripped by the blade 61 and the forward face of the notch 60 in the roller 50 so that 90 the creased edge at the center of the blank 95 is fed forward and downward between the lower doubling roller 60 and the roller 56, the ends 24 and 25, see Fig. 12, being doubled together and the connection between 100 this blank and the next succeeding blank 105 being cut by the blade 75 on the top roller 51 acting in conjunction with the cutting block 76 on the lower roller 50. From here 110 the blank goes to the folding rollers and plows 80 and 81 which turn the edge flaps 115 27, 28 and 29, already paste-coated as described, along the dotted lines 30 and over the adjacent edges of the smaller and flapless portion of the blank. The blank with 120 the flaps thus folded is then fed downward 125 to the drying wheel, whence it is delivered to the drying wheel, whence it is delivered in finished condition.

I have thus described my invention specifically and in detail in order that its nature and operation may be fully understood; 130

UNITED STATES PATENT OFFICE.

ANDREW G. BRANDT, OF SCRANTON, PENNSYLVANIA.

BUTTON-FASTENER.

1,214,505.

Specification of Letters Patent.

Patented Feb. 6, 1917.

Application filed July 1, 1915. Serial No. 37,552.

To all whom it may concern:

Be it known that I, ANDREW G. BRANDT, a citizen of the United States, residing at Scranton, in the county of Lackawanna and State of Pennsylvania, have invented a new and useful Button-Fastener, of which the following is a specification.

The device forming the subject matter of this application is a button, and the invention aims to provide novel means whereby the eye-forming element may be maintained detachably interlocked with the body.

In the accompanying drawing:—Figure 1 is a rear elevation showing the button hereinafter described; Fig. 2 is a section taken in a plane parallel to the body portion of the button; Fig. 3 is a transverse section; Fig. 4 is a front elevation.

In carrying out the invention as shown in Figs. 1, 2, 3 and 4, the body portion of the button appears at 24 and is provided with a transverse groove 25 in which is mounted a loop-shaped strip 26 comprising spaced walls. In one end of the loop-shaped strip 26 there is fashioned an opening 27, the other end of the strip being formed into a bearing 28. Slidably mounted between the walls of the strip 26 and movable in the opening 27 is a fastening member 31 in the form of a link having converging arms, the fastening member surrounding a securing device 29 which holds the strip 26 to the body 24 of the button, the securing device having a head 30 engaging the outer face of the body 24 of the button as shown in Fig. 4. Mounted to rock in the bearing 28 is the intermediate portion 32 of an eye-forming member or hasp comprising U-shaped, resilient arms 33 disposed parallel to each other, the ends 34 of the arms 33 being pointed, and being provided with shoulders 35. The pointed ends 34 of the arms 33 pass through openings 36 in the outer wall of the loop-shaped strip 26 and through openings 38 in the inner wall of the strip, the ends 34 entering recesses 37 formed in the body portion 24.

In practical operation, the hasp is swung over in the bearing 28 until the ends 34 of the arms 33 pass through the openings 36 and 38 in the loop-shaped strip 26, the shoulder 35 interlocking with the outer wall of the strip 26. Then, if the fastening member 31 be advanced into the position of Fig. 2, its side arms will coat with the ends of the arms 34 of the eye-forming member and maintain the shoulders 35 interlocked beneath the outer wall of the strip 26.

Having thus described the invention, what is claimed is:—

1. In a button, a body; a keeper assembled with the body; an eye forming member pivotally assembled with the keeper and comprising arched arms adapted to interlock with the keeper; and a wedge slidably on the keeper and coacting with the arms to hold the arms interlocked with the keeper.

2. A button comprising a body; a loop-shaped strip on the body and comprising spaced walls, one end of the strip being formed into a bearing, and the other end of the strip having an opening; a securing device connecting the strip with the body; a U-shaped eye forming member mounted to rock in the bearing and including arched resilient arms, the strip having openings in which the ends of the arms are received; and a wedge-shaped link surrounding the securing device and mounted to slide between the walls of the strip, the link being accessible through the first specified opening, and coacting with the inner edges of the arms of the eye forming member, adjacent the ends of said arms.

In testimony that I claim the foregoing as my own, I have hereto affixed my signature in the presence of two witnesses.

ANDREW G. BRANDT.

Witnesses:

HELEN O'MALLEY,
J. E. WATKINS.
